UNITED STATES PATENT OFFICE

153,793

DESIGN FOR A COMBINATION CONTAINER FOR COSMETICS AND CLOSURE THEREFOR

Frank P. Hageman, Vincent I. Mora, and Herbert C. Richardson, Minneapolis, Minn., assignors to Duncan Storm Ltd., Inc., Minneapolis, Minn., a corporation of Delaware

Application November 2, 1946, Serial No. 134,483

Term of patent 3½ years

(Cl. D58—8)

To all whom it may concern:

Be it known that we, Frank P. Hageman, Vincent I. Mora and Herbert C. Richardson, all citizens of the United States of America, and residing in the city of Minneapolis, county of Hennepin, State of Minnesota, have invented a new, original, and ornamental Design for a Combination Container for Cosmetics and Closure Therefor, of which the following is a specification, reference being made to the accompanying drawing forming a part thereof, wherein:

Fig. 1 is a perspective view of a combination container for cosmetics and closure therefor, showing my new design.

Fig. 2 is a perspective, exploded view showing the said container with the closure detached.

Fig. 3 is a front elevation of the container with closure applied.

Fig. 4 is a top plan view of the same; and

Fig. 5 is a bottom plan view of the closure removed.

We claim:

The ornamental design for a combination container for cosmetics and closure therefor, substantially as shown.

FRANK P. HAGEMAN.
VINCENT I. MORA.
